(57) **CLAIM**

The ornamental design for a scrub top, as shown and described.

DESCRIPTION

FIG. 1 is a front perspective view of a scrub top showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a front view thereof showing the claimed design in an environment in which it may be used.

The dashed broken lines in the figures show portions of the scrub top and environment that form no part of the claimed design.

The dot-dash broken lines in the figures show boundaries that form no part of the claimed design.
